HAROLD H. ELLISTON, OF INDEPENDENCE, KANSAS

EVAPORATING APPARATUS

Application filed May 16, 1930. Serial No. 452,946.

This invention relates to an evaporating apparatus and method of using the same, and it has, for its object, to provide an evaporating apparatus of marked efficiency, capable of use in many fields of industry, but, particularly, adapted and intended for use in disposing of the salt water that is brought to the surface of the ground, in the production of oil and gas from wells.

10 The problem of disposing of this salt water becomes increasingly great each year. Every large oil company is continually confronted with claims for salt water damage, because of the pollution of streams and wells, and 15 injury to the land caused either by direct passage of the salt water over the surface of the land or subterranean leakage of ponds built by the oil companies to retain the water. Many States have enacted statutes prohibiting 20 the permitting of salt water to flow over the surface of the ground or into streams, and it becomes increasingly important to provide a practicable and economical method of meeting 25 this situation.

25 An apparatus adapted to accomplish the foregoing object is illustrated in the accompanying drawings, wherein

Fig. 1 is a vertical sectional view of an apparatus constructed in accordance with the invention,

Fig. 2 is a horizontal sectional view therethrough, on line 2—2 of Fig. 1,

Fig. 3 is an elevation with the outer jacket in section and the inner jacket in elevation, 35 and

Fig. 4 is a view like Fig. 3, but at right angles thereto.

Like numerals designate corresponding parts in all of the figures of the drawings.

40 The evaporating apparatus of the present invention comprises an outer wall 5, and an inner wall 6, the space between these two walls constituting a liquid jacket 7. Wedge shaped compartments 8, 9, 10, 11 and 12, project from the opposite side walls of the inner walls 6, these compartments being fluid tight except for the entrance and exit ports or pipes hereinafter described. Two webs 13—14 are disposed within the space bounded by the inner walls 6, these webs being of zig-zag

formation and lying in spaced relation to each other. The web 13 comprises alternate riffle plate sections 15, 16, 17 and plane sections 18, 19 and 20, connected by the vertical portions 21, 22, 23, 24 and 25. The web 14 comprises the alternate riffle plate sections 26, 27, and 28, and plane sections 29, 30, connected by the vertical portions 31, 32 and 33—33^a. The webs and the wedge shaped partitions are so arranged, with respect to each other, as to form three separate paths, indicated by the arrows *a*—*b*—*c*. The arrows *a* and *c* indicate the path of travel of heat from chambers 34 and 34^a, which may contain gas burners indicated by pipes 35, 35^a, or may receive products of combustion from external sources, as, for example, from an internal combustion engine, or engines, through said pipes 35, 35^a. The path *b* is a course of liquid travel over the riffle plates, 60 as will be hereinafter described.

When salt water is produced from a pumping oil well it is separated from the oil in a separator which is located from 10 to 15 feet above the surface of the ground. 75 The water, consequently, may be conducted by gravity to the evaporator and delivered therein through a pipe A at the lower portion of the waterjacket. From the water jacket the water is delivered through a port B, 80 into the uppermost wedge shaped chamber 8 (see Fig. 4). It circulates through said chamber across the width of the apparatus and leaves the chamber through a pipe C, which extends obliquely across one side of 85 the inner casing and around the corner of said casing to the rear side of the wedge shaped chamber 9, entering said chamber at D, leaving said chamber through pipe E, which extends obliquely across the inner 90 wall 6, and enters the wedge shaped chamber 10 at F. The water leaves the chamber 10 through a pipe G, which extends obliquely across the inner wall of the water jacket and enters the wedge shaped chamber 11, 95 at H. It leaves chamber 11 through pipe I, which extends obliquely across the apparatus and enters the wedge shaped chamber 12, at J. This movement of the crude salt water through the wedge shaped chambers is 100

for the purpose of pre-heating it. From the lowermost chamber 12, the now heated water is conducted through a pipe K, and discharged through a downturned leg k, of said pipe, into a trough 36. The water overflows the lip of its trough and cascades, successively, over riffle plates 15, 26, 16, 27, 17 and 28, entering a compartment 37 through the channel 38, the lower end of which is disposed below the level of an overflow pipe 39, with the result that a liquid seal is maintained at the lower end of the channel 38. It will be observed that both the upper and lower surfaces of the riffle plates are disposed to receive heat from either the channel a or c, the hot gases passing from the apparatus through the passages 40 and 41, and the vapors passing from the apparatus, at 42.

It is to be understood that the construction illustrated in the accompanying drawings is merely exemplary, and that the number of riffle plates and the number of pre-heating compartments or chambers, 8, 9, etc., may be multiplied to any desired extent. There is a considerable degree of waste heat available in the modern well pumping plants, and the number of riffle plates may be increased to the point where all of the heating capacity of the plant may be utilized in the evaporation process.

Since the water passage b is water sealed by terminating beneath the liquid level in compartment 37, it follows that the evaporation of the liquid may be carried out under sub-normal pressures, by virtue of which the efficiency of the apparatus is further increased. It will be observed that the riffle plates constitute a series of stairs with risers at the lower sides thereof, so that the liquid is forced to run in a wide shallow sheet over the entire surface of the riffle plate and make the entire surface available for direct heat transfer to the liquid by the hot gases passing directly under and over these riffle plates. The number of riffle plates which will be installed in any one apparatus will usually be governed by the temperature of the outgoing gases or products of combustion. By virtue of the apparatus herein shown and described, the volume of salt water which must be disposed of may be reduced to a relatively small quantity of concentrated liquid which leaves the compartment 37 through the overflow pipe 39, and this is in such volume that it may be readily disposed of without contamination of adjacent lands, streams, or the like.

It is to be understood that the invention is not limited to the particular arrangement shown and described, but that it includes within its purview whatever changes fairly come within either the terms or the spirit of the appended claims.

Having described my invention, what I claim is:

1. An evaporating apparatus of the character described, comprising an inner chamber surrounded by a water jacket, a pair of zig-zag webs, each comprising a plurality of riffle plates, said webs lying in internested but spaced relation, and the spaces between said webs constituting a course of water travel, means for conducting a liquid to be vaporized through the water jacket to pre-heat the same, means for delivering the liquid to be vaporized to the uppermost of the riffle plates, and wedge shaped compartments projecting alternately from the opposite sides of the inner chamber, the upper and lower faces of which lie in substantial parallelism with the adjacent portions of the respective webs, the interiors of said compartments constituting parts of the path of travel of the liquid through the water jacket. 75

2. A device of the character described, comprising an inner compartment surrounded by a water jacket, a plurality of closed wedge shaped compartments projecting alternately in opposite directions from the opposite inner side walls of the water jacket and into said inner compartment, a pair of zig-zag webs, each shaped to form a plurality of riffle plates and plane portions connected by vertical runs, said webs lying in internested but spaced relation with respect to each other, and with respect to the faces of said closed chambers, the space between the confronting faces of the webs constituting a course of water travel, and the spaces between the respective webs and their associated closed chambers constituting courses of heat travel, and means for conducting a liquid to be vaporized to the water jacket, and means for conducting the said liquid from the said water jacket successively through the several closed chambers, and means for conducting said liquid from the last of said closed chambers to the uppermost of the riffle plates. 100

3. A device of the character described, comprising an inner compartment surrounded by a water jacket, a plurality of closed wedge shaped compartments projecting alternately in opposite directions from the opposite inner side walls of the water jacket and into said inner compartment, a pair of zig-zag webs, each shaped to form a plurality of riffle plates and plane portions connected by vertical runs, said webs lying in internested but spaced relation with respect to each other, and with respect to the faces of said closed chambers, the space between the confronting faces of the webs constituting a course of water travel, and the spaces between the respective webs and their associated closed chambers constituting courses of heat travel, means for conducting a liquid to be vaporized to the water jacket, means for conducting the said liquid from the said water jacket successively 110

through the several closed chambers, means for conducting said liquid from the last of said closed chambers to the uppermost of the riffle plates, and a liquid compartment at the lower portion of the apparatus into which the liquid is finally discharged and in which the said water channel is water sealed.

4. A device of the character described, comprising an inner compartment surrounded by a water jacket, a plurality of closed wedge shaped chambers projecting alternately in opposite directions from the opposite inner side walls of the water jacket and into said inner compartment, a pair of zig-zag webs, each shaped to form a plurality of riffle plates and plane portions connected by vertical runs, said webs lying in internested but spaced relation with respect to each other, and with respect to the faces of said closed chambers, the space between the confronting faces of the webs constituting a course of water travel, and the spaces between the respective webs and their associated closed chambers constituting courses of heat travel, means for conducting a liquid to be vaporized to the water jacket, means for conducting said liquid from the said water jacket successively through the several closed chambers, means for conducting said liquid from the last of said closed chambers to the uppermost of the riffle plates, a liquid compartment at the lower portion of the apparatus into which the liquid is finally discharged and in which the said water channel is water sealed, and a concentrated liquid outlet from the last named compartment.

In testimony whereof I affix my signature.
HAROLD H. ELLISTON.
